UNITED STATES PATENT OFFICE.

FRANK GOSZTYLLA, OF DETROIT, MICHIGAN.

DESIGN FOR A POCKET-KNIFE.

49,334.

Specification for Design.

Patented July 11, 1916.

Application filed March 23, 1916, Serial No. 86,319. Term of patent 7 years.

To all whom it may concern:

Be it known that I, FRANK GOSZTYLLA, a subject of the Emperor of Austria-Hungary, residing at Detroit, in the county of Wayne and State of Michigan, have invented a new, original, and ornamental Design for a Pocket-Knife, of which the following is a specification, reference being had to the accompanying drawing, forming part thereof.

The figure is a view in side elevation of a pocket knife, showing my new design.

I claim:—

The ornamental design for a pocket knife, as shown.

FRANK GOSZTYLLA.
